C. H. ALLISON:
EXPLOSIVE CAP PROTECTOR.
APPLICATION FILED MAR. 16, 1915.

1,163,965.

Patented Dec. 14, 1915.

UNITED STATES PATENT OFFICE.

CHARLES H. ALLISON, OF GLENDALE, CALIFORNIA.

EXPLOSIVE-CAP PROTECTOR.

1,163,965.

Specification of Letters Patent. Patented Dec. 14, 1915.

Application filed March 16, 1915. Serial No. 14,805.

To all whom it may concern:

Be it known that I, CHARLES H. ALLISON, a citizen of the United States, residing at Glendale, in the county of Los Angeles, 5 State of California, have invented new and useful Improvements in Explosive-Cap Protectors, of which the following is a specification.

This invention relates to a protector for 10 explosive caps and to improvements upon the explosive cap protection for which Patent No. 1,094,692 was issued to me on April 28, 1914; and the present improvement consists particularly in certain changes 15 designed to adapt my protector more efficiently for use in extremely high water pressures. In some instances, where using the protection described in my said patent, it has been found that the water pressure at a mile or 20 more in depth has been sufficient to crush the cap within the protecting envelop. The caps are never completely filled with the detonating substance, some air voids always being left within the caps; and I have found 25 that under extremely heavy pressures, as of a depth of a mile or more in water, the caps themselves may be compressed and premature explosion may possibly occur or the cap may be so deformed that detonation 30 is impossible. No water reaches the cap under any circumstances.

The present improvement has as its object 35 the prevention of this crushing or deforming by extremely great water pressure; at the same time retaining the advantages inherent in my original protection as described in said patent. I form an envelop 40 of asphalt or other suitable material about the cap or bundle of caps, the asphalt being carefully kneaded into a solid voidless mass about the cap; and then, while the envelop is still plastic, it is inserted in a casing of glass or other suitable material, being pressed into the casing so that there are no 45 voids whatever within the casing. The casing, preferably in halves, is held together around the envelop and cap by any suitable means. I prefer to halve the casing and to hold it together by a casing of rubber tape; 50 but this may be as desired. The material of the casing is of great pressure resisting strength, having not only its own pressure resisting strength but being supported from the inside by having the solid mass of asphalt or other material filling its entire interior without any voids. By this construction 55 I have the advantage of the kneaded

envelop around the cap and also have the advantage of a physically strong casing which will support a great fluid pressure, 60 but which is fragile and easily broken by detonation on the inside.

I have shown the improved form of my protector in the accompanying drawings, in which—

Figure 1 is a longitudinal section of a 65 protector inclosing a bundle of caps, Fig. 2 is a transverse section of the same, Fig. 3 is an exterior view of the same and Fig. 4 is a longitudinal section showing a modified form of the protector inclosing a single large cap.

In the drawings, the numeral 10 designates caps, which may be associated in any number in a bundle, and 11 designates the 70 envelop of asphalt or any other suitable material which is kneaded about the cap and into spaces between them, forming a voidless mass which itself is practically incompressible. I prefer to use asphalt for 75 this purpose for the reasons set forth in my former patent; because the asphalt is hard and will withstand great compressive pressure, and is brittle and easily disrupted by detonation from within, and can be rendered 80 plastic by heating to a temperature which cannot detonate the cap.

The casing 12 is made preferably in two 85 halves separated on a central longitudinal plane. The casing is preferably cylindrical 90 with rounded ends; and at the ends there are two apertures for the passage of the wires 14 leading to the caps. The halves of the casing may be joined by such a joint as is shown at 15 in Fig. 2, so that the halves 95 are registered in correct position. This casing is preferably made of glass or other similar material, which will offer great resistance to fluid compression from the outside but which is easily disrupted by 100 detonation from the inside.

The asphalt envelop 11 is worked around the caps until it assumes approximately the shape and size of the interior of the casing, preferably slightly smaller than the interior. 10 The mass of the envelop is still plastic when it is inserted in the casing. To add to the plasticity of the exterior part of the envelop, the kneaded mass is dipped in heated liquid asphalt just prior to being inserted in 110 the casing; and this heated liquid asphalt is sufficiently plastic and fluid to cause an absolutely voidless fit of the asphalt mass within the casing. The cap, being protected by

the thick mass of asphalt around it, at a comparatively low temperature, the high temperature of the fluid asphalt adhering to the outside of the mass does not reach the cap. After the heated mass is dipped in the hot liquid asphalt, it is quickly placed in one half of the casing and the other half of the casing is then brought down in proper position over the asphalt mass; and all of 10 the excess asphalt squeezed out through the wire apertures 13. This operation is performed with the halves of the casing in a device, something similar to a common lemon squeezer, with places in its opposite sides 15 for reception of the halves of the casing.

After the casing has been placed around the mass of asphalt, and the excess asphalt squeezed out through the end openings, the asphalt is kneaded about the end opening 20 and about the wires projecting therethrough and a covering is then placed around the whole, as shown at 16. This covering may preferably be a rubber casing tightly drawn around the casing and around the ends where 25 the wires emerge, to physically protect the casing from breakage and also to hold the halves of the casing together.

In Figs. 1, 2, and 3 I have illustrated a form of my protector to hold a bundle of 30 small caps; while in Fig. 4 I have illustrated a form which holds a single large cap 10. The construction is essentially the same as hereinbefore described, excepting that the casing 12 is longer and more slender than 35 that designed to hold a bundle of caps. This form of protector is especially useful in operations where rotary drilling rigs are used, where it is necessary to lower the explosive charge through the hollow drill pipe and 40 drill stem.

In my proved form of protector as herein described, I retain all of the advantages of my former protection, together with the advantageous feature of the casing 12 which 45 protects the caps from rupture or distortion by extremely heavy water pressure. The casing is not only strong in itself, but it is supported by the solid incompressible mass of asphalt in its interior; and the water pressure 50 sure from the outside is partially transmitted to the interior of the casing through the asphalt extending through the apertures 13, thus partially balancing the pressures inside and outside the glass casing. The glass casing, although it thus protects the cap from 55 deformation and from being crushed, does not materially damp the detonative action of the cap, being fragile and easily broken.

Having described my invention, I claim: 60 1. An explosive cap protector, comprising an envelop of water proof material kneaded about the cap in a solid mass, a casing surrounding said envelop, said casing being

parted so that the kneaded envelop may be fitted without voids into the casing, and an 65 exterior covering around the casing.

2. An explosive cap protector, comprising an envelop of water proof material kneaded about the cap while plastic, a parted casing capable of resisting great fluid pressure into 70 which casing the kneaded envelop and caps are inserted while the envelop is plastic, and an exterior covering around the casing.

3. An explosive cap protector, comprising an envelop of asphalt kneaded about the cap, 75 a parted glass casing into which the envelop is inserted while plastic, and a covering over the glass casing.

4. An explosive cap protector, comprising an envelop of asphalt kneaded about the cap, 80 a parted glass casing into which the envelop is inserted while plastic, and a taping surrounding the glass casing to hold the halves together and to protect it from breakages.

5. An explosive cap protector, comprising 85 an envelop of water proof material kneaded about the cap in a solid mass, and a casing surrounding the kneaded mass, said casing being parted so that the kneaded mass may be fitted thereinto without voids. 90

6. An explosive cap protector, comprising an envelop of water proof material kneaded about the cap in a solid mass, and a casing of vitreous material surrounding the kneaded mass, said casing being parted so that the kneaded mass may be 95 fitted thereinto without voids.

7. An explosive cap protector, comprising an envelop of water proof material kneaded about the cap in a solid mass, and a thick 100 rounded casing of vitreous material surrounding the kneaded mass, said casing being parted so that the kneaded mass may be fitted thereinto without voids.

8. An explosive cap protector, comprising 105 an envelop of water proof material and an exterior casing of vitreous material.

9. An explosive cap protector, comprising an envelop of water proof plastic material formed about the cap while plastic, and an 110 exterior casing of vitreous material.

10. An explosive cap protector, comprising an envelop of water proof material and a thick exterior casing of a vitreous material.

11. An explosive cap protector, comprising 115 an envelop of water proof plastic material formed about the cap while plastic, and a rounded thick exterior casing of vitreous material.

In witness that I claim the foregoing I 120 have hereunto subscribed my name this 10th day of March 1915.

CHARLES H. ALLISON.
